UNITED STATES PATENT OFFICE.

WILLIAM WHARTON, JR., AND EDWARD SAMUEL, OF PHILADELPHIA,
PENNSYLVANIA, ASSIGNORS TO WILLIAM WHARTON, JR., AND COMPANY,
INCORPORATED, OF SAME PLACE.

DESIGN FOR A RAILWAY-RAIL.

SPECIFICATION forming part of Design No. 18,328, dated May 15, 1888.

Application filed April 20, 1888. Serial No. 271,341. Term of patent 14 years.

To all whom it may concern:

Be it known that we, WILLIAM WHARTON, Jr., and EDWARD SAMUEL, both citizens of the United States, and residents of Philadelphia, Pennsylvania, have invented a new and original Design for a Railway-Rail, of which the following is a specification.

Our design for a railway-rail is fully shown in the accompanying drawing, which represents a transverse section of the rail.

The rail has a depending web, W, at the top of which, on one side, is a laterally-projecting head, P, both the upper and under faces of which extend straight to the outer edge. From the opposite side of the web projects a neck, N, at the outer end of which is a vertical flange, F, which projects both above and below the neck. The upper projecting portion forms a rib, a, between which and the head P of the rail is a deep groove, b, and the lower project-

ing portion of the flange forms a lug, d, between which and the web W is a groove, f.

We claim—

The herein-described design for a railway-rail having in transverse section the outline illustrated, comprising the depending web W, laterally-projecting head P, with straight upper and under faces, and laterally-projecting neck N, terminating in a flange, F, with upper projecting rib, a, and lower projecting lug, d, all substantially as described and shown.

In testimony whereof we have signed our names to this specification in the presence of two subscribing witnesses.

WILLIAM WHARTON, JR.
EDWD. SAMUEL.
